Inventor

Wilbert C Clarkson

Patented Feb. 3, 1925.

UNITED STATES PATENT OFFICE.

MILBERT C. CLARKSON, OF KANSAS CITY, MISSOURI.

OUTSIDE WINDOW WASHER.

Application filed August 4, 1923. Serial No. 655,587.

To all whom it may concern:

Be it known that I, MILBERT C. CLARKSON, a citizen of the United States, residing at Kansas City, in the county of Jackson, son and State of Missouri, have invented certain new and useful Improvements in an Outside Window Washer, of which the following is a specification.

This invention relates to window cleaners and more particularly to an improved apparatus especially designed for cleaning the outside surface of window-panes.

The primary object of the invention is to provide a manually operated apparatus which may be manipulated by an operator on the inside of a room so that the exterior surface of the window-pane may be cleaned, wiped or dried.

The invention has for another object a device which may be extended across the window sill of a window and supported on the window sill so that an operator may conveniently operate the movable part to cause the cleaning element to be moved over the exterior surface of the window-pane.

Other objects of the invention will appear upon consideration of the following detailed description and accompanying drawings in which:

30 Figure 1 is a perspective view of the apparatus constructed in accordance with my invention.

Figure 2 is a side elevation of the same, parts being broken away to more clearly 35 disclose the mechanism.

Figure 3 is an end elevation.

Referring to the drawings by numerals, a supporting bar 1 is provided to support the apparatus and is provided on one end 40 with a clip 2 which is adapted to embrace the inner edge of the window sill so that the supporting bar will be properly held in position. The supporting bar 1 is long enough to extend considerably beyond the 45 outside edge of the window sill as shown to advantage in the drawing and is equipped with a longitudinal slot 3 extending throughout the greater portion of the length of the supporting bar. The cleaning element 4, of 50 the conventional type, is adapted to travel over the surface of the window-pane and obviously it may consist of a brush, wiper, or drying element. This element 4, is connected by a connecting rod 5 to the supporting bar 1 by a pin 6 which is adapted 55 to travel in the longitudinal slot 3. This

pin 6 is connected to one end of one of the operating rods 7 which extends in parallel relation to the supporting rod and across the window sill, the inner end being so disposed as to permit the operator to readily take hold of the member 7 when the device is to be operated. A complementary operating rod 8 is attached by a pin 9 to the connecting arm 5 at a point 60 above the supporting rod or bar 1 so that two connections with operating members 7 and 8 are thus made with the connecting arm 5. The rod 8 is disposed above the rod 7 so that they may be moved longitudinally to impart movement to the arm 5. 65

When the apparatus is in use it will be mounted on the window sill as shown in Figure 1 of the drawing and the operator may grasp the ends of the rods 7 and 8, and impart reciprocatory motion thereto thus swinging the operating arm 5 and causing the pin 6 to move longitudinally in the slot 3 thus imparting motion to the upper end of the arm 5 whereby the cleaning 70 element 4 will be moved over the surface of the glass on the outside of the window-pane.

Minor changes may be made in the details of construction without departing from the spirit of the invention or the scope of the 75 claims hereunto appended.

What I claim is:

1. In an apparatus of the character described, a supporting bar, an operating arm, a cleaning element mounted on the end of the operating arm, the said supporting bar being equipped with a longitudinal slot, means connecting the operating arm to the said bar through the said longitudinal slot, and a pair of operating rods connected to the operating arm whereby a reciprocatory motion may be imparted to the operating arm for readily moving the said cleaning element.

2. In an apparatus of the character described, a supporting bar having a longitudinal slot therein, an operating arm connected to said supporting bar through said longitudinal slot, a cleaning element attached to one end of said operating arm, a pair of spaced pins carried by said operating arm, a pair of operating rods arranged in parallel relation to each other and each having one end thereof connected to said pins whereby a reciprocatory motion may 100 be imparted to said operating rods for moving said operating arm.

3. A window cleaner, comprising a supporting bar, means for supporting said bar on a window sill, an operating arm, means for slidably connecting said operating arm to said supporting bar, a cleaning element attached to said operating arm and adapted to engage the outside surface of a window-pane, and a pair of operating rods connected to said operating arm and adapted 10 to be alternately reciprocated to impart a

swinging motion to said operating arm whereby said cleaning element will be moved over the surface of the window-pane.

In testimony whereof, I have affixed my signature in the presence of two witnesses.

MILBERT C. CLARKSON.
